(57) **CLAIM**

The ornamental design for a light assembly, as shown and described.

DESCRIPTION

FIG. 1 is a front, right, and bottom perspective view of a first embodiment of a light assembly, showing our design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right, and bottom perspective view of a second embodiment of the light assembly showing 2 additional lighting parts on the body of the light assembly; and, FIG. 10 is a front, right, and bottom perspective view of a third embodiment of the light assembly showing 4 additional light parts on a body of the light assembly.

The broken lines shown in the drawings are included for the purpose of illustrating portions of the light assembly that form no part of the claimed design.

The light assembly is shown with symbolic breaks in its length. The appearance of any portion of the article between the break lines forms no part of the claimed design.
